UNITED STATES PATENT OFFICE.

ERNST A. PLOEGER AND JOHN PENROSE, OF CHICAGO, ILLINOIS.

AUTOMATIC RELIEF-VALVE.

1,242,888.

Specification of Letters Patent.

Patented Oct. 9, 1917.

Application filed September 25, 1914. Serial No. 863,591.

To all whom it may concern:

Be it known that we, ERNST A. PLOEGER and JOHN PENROSE, citizens of the United States, residing at Chicago, in the county of Cook and State of Illinois, have invented certain new and useful Improvements in Automatic Relief-Valves, of which the following is a description.

Our invention relates to that general class of devices known as traps or water relief valves, employed upon various steam or other systems to discharge water of condensation or other fluid without any unnecessary waste or loss of steam. The invention has among its objects the production of a device of the kind described that is simple, efficient, durable and satisfactory, which is automatic in operation, and which will not accumulate sediment or foreign material within the valve casing, nor be affected or rendered inoperative by sediment or accumulations of dirt flowing through the casing. To this end our invention consists in the novel construction, arrangement or combination of parts herein shown and described, and more particularly pointed out in the claims.

In the drawings, wherein like reference characters indicate like or corresponding parts,

Figure 1 is a partial sectional view of the preferred form of our device;

Fig. 2 is a cross sectional view taken substantially on line 2, 2 of Fig. 1; and

Fig. 3 is a cross sectional view taken on line 3, 3 of Fig. 1.

Referring to the drawings, our device consists of a suitable casing 1, which is provided with a top or cover 2, which, in the preferred form, is made removable. The casing is provided with an inlet 3 and outlet 4, the inlet 3 being through an extension 5 at one side of the casing, and the outlet 4 through an extension 6, arranged centrally at the bottom of the casing. It will be particularly noted that the mouth of the outlet is substantially even with the bottom of the inlet, so that there is no chance for foreign material to accumulate or be obstructed in its passage through the casing. The casing bottom is also made sloping for the same reason. Arranged within the casing is a suitable float member 7, which in the form shown, is in the form of an inverted cup and is provided with a depending tubular part 7' at the center, which carries a tubular

valve member 8 at its lower end arranged to coöperate with a valve seat 10 carried by the casing at the mouth of the outlet. The valve 8 is tubular in formation and carries one or more prongs 9, 9, which serve to guide the valve member and center it during its movement in seating. The valve member 8 and stem 7' may be of one piece, if desired. The valve seat is preferably formed on a separable piece 11 of suitable material, so that the valve seat may be renewed or adjusted from time to time, as may be found necessary. It may be provided with notches 14, or the equivalent, for engagement with a suitable tool in removing or replacing the same. It will be noted that the valve float 7 is open at the bottom, this type of float being found very satisfactory for the purpose.

The float and valve member are supported, centered and guided at the top by an adjustable rod or stem 12, which limits the movement of the float, upon which are arranged spring members 15 and 16. It will be seen that the spring members 15 and 16 are disposed upon the stem 12 carried by the upper portion of the casing and entering a central opening in the float 7 yieldably support the float during its movement and also serve to limit the up and down movement of the float. The springs cause the valve to have a steady movement when rising from its seat or returning thereto and prevent the lower end thereof from being tightly jammed upon its seat which would injure the same, and also eliminate any danger of injuring the float by forcing the same into contact with the upper wall of the casing. The spring member 15 is carried by the end 12', while the spring 16 is arranged between the float and cover the top 2, the same being supported by the float.

The stem 12 projects through the cover and is preferably formed as at 17, or the equivalent, for engagement by a suitable wrench or key, the construction being so that an unauthorized person without a key cannot vary the adjustment of the device, (not shown). A pin 18, or equivalent means, is also provided for limiting the downward movement of stem 12. If desired, a cap 19 may be arranged as shown over the end 17, so as to keep all dust and dirt from accumulating at the end of stem 12 in the cover, and prevent leakage of air, steam or water from the casing. It may be mentioned that

the cover is preferably formed in the shape of a nut, as at 20, for convenience in engaging the same with a wrench to remove or replace the cover.

5 Assuming that the valve is closed, as indicated by the dotted lines: The steam is free to enter the valve casing, and owing to the suction of the vacuum apparatus, any air and a portion of the steam may pass 10 through the top of the float, about the rod or stem 12, or through the leakage port, and down the central chamber, through the valve into the discharge outlet. The opening, however, is so small that the waste of 15 steam is insignificant. Should water be discharged into the casing through the inlet and accumulate either gradually or suddenly for any reason in quantities, it will raise the float, thereby raising the valve 8, 20 and the water will flow through the discharge outlet to where desired. As the water is discharged the valve will gradually lower into place, being guided and centered by the guiding members 9 at the bottom. 25 The stem 12, however, projecting through the top of the float, always keeps the small outlet or leakage port open. The valve may be positively opened at any time, or the adjustment varied by turning the stem 12. 30 It will be noted that where the valve is raised it is entirely away from the seat. There being no obstructions in the casing to impede the passage of dirt or sediment, the casing is thoroughly washed out and cleaned 35 each time the valve is raised. The device is entirely automatic in operation, and noiseless, and there being but practically one movable part, there is nothing to be disarranged or get out of order. Should the 40 renewable valve member seat 11 become worn it may be replaced or readjusted.

Having thus described our invention, it is obvious that various immaterial modifications may be made in the same without departing from the spirit of our invention; 45 hence we do not wish to be understood as limiting ourselves to the exact form, construction, arrangement or combination of parts herein shown and described or uses 50 mentioned.

What we claim as new and desire to secure by Letters Patent is:—

1. In a device of the kind described and in combination, a suitable casing provided 55 with an inlet and outlet, a float member arranged within said casing and having an opening therethrough at the top thereof, a valve member for said outlet, said valve member carried by said float, and means 60 loosely extending through the opening in the top of the member for limiting the up and down travel of the float.

2. In a device of the kind described and in combination, a suitable casing provided 65 with an inlet and outlet, a float member ar-

ranged within said casing and having an opening therethrough at the top thereof, a tubular valve member for said outlet, said valve member carried by said float, and adjustable means loosely extending through the top opening of the float for limiting the raising and lowering of the float.

3. In a device of the kind described and in combination, a suitable casing provided with an inlet at one side, and with a centrally arranged discharge outlet at the bottom, said casing provided with a valve seat at said outlet, a vertically movable tubular valve member arranged to coöperate about its periphery with said valve seat, controlling means for said valve member comprising a float member arranged within the casing and operatively connected with said valve member, said float member having an opening through the top communicating with the interior of the valve member, and means loosely extending through the opening in the top of the float member for limiting the upward and downward movement of said float.

4. In a device of the kind described and in combination, a suitable casing provided with a detachable top and with an inlet at one side and a discharge outlet at the bottom, a controlling tubular valve for said outlet provided with means for controlling the same comprising a float secured thereto having an opening through the top thereof communicating with the interior of said tubular valve and open at its lower side, 100 said casing provided with a separable seat for said valve member, arranged to coöperate with the outer side of the tubular valve member wall, and adjustable means for limiting the movement of the valve, comprising a rod carried by the top and loosely projecting into the float through the opening in the top thereof and resilient means carried by said rod and engaging the float.

5. In a device of the kind described and in combination, a suitable casing provided with an inlet and an outlet, an inverted cup-shaped float member arranged in said casing and provided with a downwardly extending centrally disposed tubular part, a 115 tubular valve member arranged at the lower end of said tubular part and arranged to coöperate with a suitable valve seat at said outlet, said float member having an opening at the top communicating with the interior of said tubular part and valve member, and means loosely projecting through said opening into the valve member for limiting the upward and downward movement of the float.

6. In a device of the kind described and in combination, a suitable casing having an inlet and outlet, and provided with a valve seat at said outlet, a tubular valve member arranged to coöperate with said valve seat,

and provided with a tubular stem extending to proximate the upper part of the casing, a float member arranged on the upper end of said stem, and guiding means for said 5 valve and float, comprising a rod carried by the casing and loosely projecting through the float into the valve stem, and means arranged at the bottom of the valve and operating with the valve seat for guiding 10 said valve.

7. In a device of the kind described, and in combination, a casing having an inlet and outlet, a float arranged within said casing and provided with an opening extending 15 therethrough, a valve carried by said float for controlling the outlet, a rod carried by the casing and entering the opening in the top of the float, and resilient means for limiting the travel of the float.

20 8. In a device of the kind described, the combination with a casing having an inlet and outlet port, a float within said casing, a valve carried by the float, a rod carried by said casing and entering an opening in the 25 float, resilient means arranged on said rod between the casing and the float and between the lower end of said rod and the float for limiting the travel of the float, substantially as described.

30 9. In a device of the kind described, the combination with a casing having an inlet

and an outlet opening, a float within said casing, a valve connected with the float for controlling the outlet opening, a member carried by said casing and disposed within 35 the interior thereof, and a yieldable means supported by said member for limiting the upward and downward movement of the float.

10. In a device of the kind described and 40 in combination, a casing having an inlet and outlet opening, a float within said casing, a valve carried by said float, and yieldable means arranged within the upper portion of the casing for limiting the upward 45 and downward movement of the float.

11. In a device of the kind described, and in combination, a casing having an inlet and outlet opening, a float within said casing having an opening therein, a valve carried 50 by said float, a member supported by the casing and entering the opening in the float, and resilient means carried by said member for limiting the travel of the float.

In testimony whereof we have hereunto 55 signed our names in the presence of two subscribing witnesses.

ERNST A. PLOEGER.
JOHN PENROSE.
